J. A. Wilson of Springfield, Mass.
Letters Patent, No. 2486, Dated Oct. 8, 1866.
Design for a Burial base.

The Schedule referred to in these Letters Patent and making a part of this same.

To all whom it may concern:

53rd Do it known that I, John A. Wilson of Springfield in
the County of Hampden, State of Massachusetts, have invented a new and Or-
namental Design for a Cuffin basket or other Burial base; and I do
hereby declare that the following is a full, clear, and exact description thereof
which will enable others skilled in the art to understand the same
reference being had to the accompanying drawing forming a part of this
specification.

The present invention relates to a new and useful Design
for the top or lid of a casket, basket or other burial case, and it
consists in raising the central portion of the side or lid of the
burial case, with the edge or edges of such raised portion made of a round
shape of, or about one quarter part of the circumference of a circle
together with forming one, or more panels in such raised portion.
Moreover, its rounded edges, whereby the beauty and finish of the top, or
cover is greatly increased, as well as its desirability and utility, as by
hollowing out such raised portion of the lid upon the inside, the capaci-
ty of the burial case is much improved.

In the accompanying plate of drawings my new design is illustrated.

Figure 1, being a plan or top view of a burial case having an
ornamental lid of the design embraced in this invention; and

Figure 2, a side view.

Similar letters of reference indicate like parts.

A, in the drawings represents the lid or top of a burial case B, which lid upon
its upper side in its central portion C, is raised with the edges D, of such raised
portion made of a circular or round shape, of, or about one quarter of the cir-
cumference of a circle. - E, raised panels formed upon the raised portion
C, of the lid in the space embraced between its rounded edges.

I claim as new and desire to secure by Letters Patent.

The Design for the top or lid of a burial case, herein described and shown in
the drawings.

The above Specification of my invention signed by me, this 29th day of August, 1866
W. W. Wilson.

W. B. Childs,

J. Smith.
